C. M. Wade
Lacy & Lacy Attorney:

UNITED STATES PATENT OFFICE.

CHARLES N. WADE, OF PATERSON, NEW JERSEY.

TRANSFER PRINTING AND DELIVERING MACHINE.

1,359,938.

Specification of Letters Patent. Patented Nov. 23, 1920.

Application filed September 19, 1918. Serial No. 254,814.

To all whom it may concern:

Be it known that I, CHARLES N. WADE, a citizen of the United States, residing at Paterson, in the county of Passaic and State 5 of New Jersey, have invented certain new and useful Improvements in Transfer Printing and Delivering Machines, of which the following is a specification.

This invention relates to an improved 10 machine for printing street car or other transfers and has as its primary object to provide a machine of comparatively simple and compact form which may be readily operated to print and deliver transfers as 15 desired.

Another object of the invention is to provide a transfer printing and delivering machine which may be employed for printing the various transfers issued at different 20 junction points along a street car or other route.

A further object of the invention is to provide a machine which will be equipped for printing the date, the time of issue, 25 and the time of expiration of the transfer, the line issuing the transfer, and the line upon which the transfer is to be used as well as the direction for which the transfer is valid.

30 A further object is to provide a machine in which the various printing members may be moved manually to operative or inoperative position and all the printing members to be used for printing a given transfer, brought into printing position by the manual operation of a single lever.

A still further object of the invention resides in the provision of means for feeding 40 a paper strip from a roll within the machine across a printing table and beneath an inked ribbon to be printed upon by the printing mechanism before being withdrawn and cut off to provide the transfers.

45 Other and incidental objects will appear during the course of the detailed description of the invention. In the drawings, wherein I have illustrated the preferred embodiment of the invention, and wherein similar reference characters designate corresponding parts throughout the several views:

Figure 1 is a longitudinal sectional view taken through the complete device,

Fig. 2 is a transverse sectional view taken on the line 2—2 of Fig. 1 and looking in 55 the direction of the arrows,

Fig. 3 is a vertical section taken on the line 3—3 of Fig. 1,

Fig. 4 is a vertical section taken on the line 4—4 of Fig. 1,

Fig. 5 is a vertical section taken on the line 5—5 of Fig. 1,

Fig. 6 is a view similar to Fig. 5 and taken on the line 6—6 of Fig. 1, and

Fig. 7 is a perspective view showing in 65 detail the carrier plate employed for the printing mechanism.

In carrying the invention into effect I employ a preferably oblong casing 10 in which is mounted a horizontal printing 70 table 11 supported by suitable brackets 12 secured to one side wall of the casing. Journaled beneath the table 11 adjacent the forward end thereof is a transverse shaft 13 upon which is mounted a roll of paper 75 14. A strip 15 is drawn from this roll around a guide roller 15' and over the table 11, the strip lying flat against the table. From the table, the free end of the strip is then continued between friction feed rollers 80 16 and through a discharge opening 17 in the front wall of the casing, being received within a discharge trough 18 extending from the said front wall to receive the portion of the strip upon which a transfer is 85 printed. The feed rollers 16 are mounted adjacent the forward end of the casing opposite the discharge opening 17 and connected to the shaft of one of the rollers is a crank 19 by which the said rollers may be 90 manually rotated for feeding the paper strip over the table. Connected to the front wall of the casing in the rear of the discharge opening 17 and at opposite sides of the said opening, are vertical guide members 20 and 95 slidably supported between these guide members is a vertically movable cutting blade 21 provided with a beveled lower cutting edge adapted to sever the paper strip 15. The blade is held in elevated position 100 by suitable springs 22 connected with opposite ends of the blade and the top wall of the casing and is manually operable by a handle 23 projecting through a suitable slot in the front wall of the casing. Extending 105 over the printing table 11 in close spaced

relation to the portion of the paper strip 15 lying thereon is an inked ribbon 24, held parallel to the said portion of the paper strip by guide rollers 25 mounted at opposite ends of the table. One end of the ribbon is wound upon a roller 26 mounted in the lower rear corner of the casing while the opposite end of the ribbon is wound upon a similar roller 27 mounted in the forward upper corner of the casing.

Suspended above the printing table 11 in spaced parallel relation thereto, is a vertically movable plate or carrier 28. Upstanding from this plate adjacent the corners thereof are lugs 29 and connected at their lower ends to these lugs are a plurality of springs 30 the upper ends of which are secured to lugs 31 depending from the top wall of the casing. Thus, the springs 30 will normally hold the plate elevated and mounted to guide the plate in its vertical movement are a plurality of rails 32. These rails are connected to opposite side edges of the plate and are received within vertical guide members 33 upon the inner faces of the side walls of the casing. As will be seen, the rails 32 will tend to maintain the plate in a horizontal plane and thus prevent sagging of either side or end of the plate.

The plate 21 carries all of the printing mechanism. The date printing mechanism comprises a shaft 34 upon which are mounted telescopic sleeves 35 and 36 respectively, extending throughout the major portion of the length of the shaft. Upstanding from the plate are spaced bearing brackets 37 and 38 respectively, the bracket 37 engaging the inner end of the shaft while the bracket 38 receives the outermost sleeve 36 for thus operatively supporting the shaft and sleeves with respect to the plate. Connected to the shaft as well as to the inner ends of the sleeves respectively, are disks 39, 40 and 41. One of the disks has numerals on its periphery to designate the different years, another has numerals thereon for the various days of the month, while the third has letters thereon to indicate the different months. At their outer ends, the shaft and sleeves project freely through a suitable elongated slot 42 in the adjacent side wall of the casing so as to permit depression of the plate 21 and respectively carry turning knobs or disks 43, 44 and 45, so that the shaft or either one of the sleeves may be independently rotated for shifting the disks 39, 40 and 41 to dispose the proper letters and numerals in active position projecting through a suitable opening 43' in the plate. As will be seen, the proper one of the disks 39, 40 and 41 may be changed each day to print the current date.

The mechanism for printing the time of issue of a transfer and the time within which the transfer must be used comprises a suitable clock mechanism inclosed within a casing 44' mounted on the plate 21 and operating a shaft 45' projecting from the casing. Mounted upon the outer end of said shaft is a gear wheel 46. Upstanding from the plate 21 in advance of the shaft 45' is a pair of spaced bearing brackets 47 arranged at opposite sides of an opening 48 through the plate. Journaled upon these brackets is a shaft 49 carrying a pinion 50 meshing with the gear wheel 46. Upstanding from the plate 21 in the rear of the shaft 45' is a pair of bearing brackets 51 arranged at opposite sides of an opening 52 through the plate. Journaled upon the brackets 51 is a shaft 53 carrying a pinion 54 also meshing with the gear 46. Thus the shafts 49 and 53 will be simultaneously rotated from the shaft 45. Fixed upon the shaft 49 is a type carrying wheel or disk 55 projecting through the opening 48 in the plate while a similar wheel or disk 56 is fixed upon the shaft 53 to project through the opening 52 in the plate. Type members are mounted upon the peripheries of these wheels and preferably indicate the hours and fractions of hours, as may be decided upon by the parties for whom the machines are provided. For illustration, the hours and half hours may be indicated by the type members upon the wheel 55, while the quarter hours are arranged upon the wheel 56. In other words, the wheel 55 will be in position for its type to print one o'clock while the wheel 56 is in position for its type to print one fifteen or, when the wheel 55 is in position for its type to print one thirty, the wheel 56 will be in position for its type to print one forty-five, always giving fifteen minutes between the time the transfer is issued and the time at which the transfer will expire. In this connection it will, of course, be understood that the wheels 55 and 56 will be properly rotated by the clock mechanism to print the current time upon the transfers. The clock mechanism is to be wound and set in the usual manner but since the winding and setting mechanism may be of any conventional character, such mechanism is not shown. However, in order to permit free access to the clock mechanism, one side wall of the casing is provided with a suitable door 57. In order to permit the removal of any of the parts or their repair, the opposite side wall of the casing is, as particularly shown in Figs. 3 to 6 inclusive, preferably hinged.

In showing and describing the printing disks or wheels 55 and 56 for printing the hour and each quarter or half of an hour as designating the time between the time of

issue and the time of expiration of the transfer, I have only illustrated by way of example, how the device is to be employed. In practical use, the disk or wheel 55 may 5 give simply the hour, or, in addition to the hour, the exact minute at which the transfer is issued, and the disk or wheel 56 will give the hour and exact minute fifteen minutes later, designating the time of expiration of 10 the transfer or vice versa. Further, the time limit for the expiration of the transfer may be ten minutes, fifteen minutes, a half hour, or any other time which is figured as proper or prescribed by law, depending upon the 15 conditions existing at the junction or transfer point. The illustration is sufficient to demonstrate the principle involved but accurate printing will avoid all possible dispute.

20 Upstanding from the plate 21 adjacent the rear end thereof is a medially arranged guide block 58 and mounted for reciprocation through this block is a plurality of plungers or type carrying members 59 arranged in pairs, and a similar type carrying member 60 at one end of the block. The plungers 59 are provided with type 61 upon their lower ends, and the plungers of each pair are connected by a walking beam or 25 rocker 62 pivoted midway of its ends upon an arm 63 upstanding from the block. The rockers are formed with forked terminals embracing the stems of the plungers and the said terminals are provided with elongated 30 slots 64 in which are slidably engaged the ends of suitable pins 65 extending through the plunger stems. The stems of the plungers project upwardly through the top wall of the casing 10 and are equipped with operating knobs 66. As will be seen, when one 35 plunger of each pair is depressed or shifted downwardly to active position so that its type 61 will project below the bottom face of the plate 21, the other plunger of such 40 pair will be shifted upwardly to inactive position. This arrangement is desirable so that the plungers may be employed for printing the direction in which the transfer is to be used, the line for which it is issued, 45 and similar data. The plunger 60 may be 50 equipped upon its lower end with type 67 for printing the name of the line issuing the transfer. Any number of plungers may be 55 provided, as desired, so that the different transfers to be issued by a line using the machine, may all be printed by any one device. The machine will, of course, be 60 designed for the various lines upon which the invention is to be employed and the number of plungers used, as well as their type, varied accordingly. Proper variation will 65 also be made in the other parts of the device according to the lines upon which the machine is to be employed. Extending from

the plate 21 centrally thereof, is an upstanding 65 operating plunger 68 which is freely received through the top wall of the casing and is provided at its upper end with an operating knob 69.

In order that each transfer may be numbered so that they may be identified and accounted for if necessary or desirable, or in order to prove conclusively that the time of issue and expiration is correct and in accordance with the order in which the transfers are issued, a numbering and recording mechanism is provided. This mechanism also records the total number of transfers issued and comprises a series of printing disks 70 mounted at one side of the guide 70 block 58 to project through the plate 28. The disks are preferably five in number and each disk carries on its periphery, numbers ranging from 1 to 9 and zero. Housing the disks is a casing 71 upstanding from the 75 plate 28 and projecting from the casing is an actuating arm 72 disposed for engagement by a trip arm 73 projecting inwardly from the adjacent side wall of the casing. Consequently, when the plate 21 is depressed 80 the arm 72 will be engaged with the arm 73 to cause the operation of the recorder and numbering device through the medium of its gearing and ratchet mechanism. The successive disks may be rotated at a ratio of 85 one to ten, so that for each rotation of the units disk, the tens disk will be stepped one space and so on, as is common in this class of devices, the disks being automatically 90 turned to again start with the number 1 95 after having reached the highest number capable of being recorded by the disks. The number of disks employed may be varied, of course, so that the mechanism may adequately serve as a recorder to indicate the 100 number of transfers issued for accounting purposes or otherwise. As will be seen, the numbering mechanism is arranged to print the transfer at the margin thereof opposite to that printed by the dating mechanism. 105

110 From the foregoing description it is believed that the operation of my improved machine will be readily understood. By manipulating the printing members, the printing members desired may be brought 115 into active or printing position, when the plunger 68 may then be operated to depress the plate 28 and print an entire transfer upon the portion of the paper strip overlying the table 11. The crank 19 is then operated to rotate the rollers 16 and feed out the printed transfer through the discharge opening 17 in the casing, when the cutting blade 21 is depressed for severing the transfer so printed. Coincident with the feeding of the printed transfer through the discharge opening, the paper strip will be advanced over the printing table in position 120 125

for printing the next transfer and this operation may be repeated until the roll 14 is exhausted, when a new roll may be readily substituted therefor.

5 While the preferred embodiment of this invention has been illustrated in the accompanying drawings and specifically described in the foregoing paragraphs, it is to be understood that minor changes in the 10 details of construction and arrangement of parts may be resorted to within the scope of the appended claims without departing from the spirit of the invention.

Having thus described the invention, what 15 is claimed as new is:

1. In a transfer printing and delivery machine, printing means including a printing member carrying a plurality of printing devices each having several printing faces, 20 means for manually selectively moving the different faces of some of said devices into printing position, time clock means for moving the different faces of others of said devices into printing position, and counting 25 means for moving the printing faces of still others of said devices into printing position.

2. In a transfer printing and delivery machine, a fixed printing table, an inking member moving adjacent the printing table, 30 means feeding a strip to be printed upon across said table between said inking member and table and delivering the same, after printing, in predetermined ticket lengths, printing means including a printing member carrying a plurality of printing devices 35 each having several printing faces, means for manually selectively moving the different faces of some of said devices into printing position, and automatic means for 40 moving the different faces of others of said devices into printing position.

3. In a transfer printing and delivery machine, a fixed printing table, an inking member moving adjacent the printing table, 45 means feeding a strip to be printed upon across said table between said inking member and table and delivering the same, after printing, in predetermined ticket lengths, printing means including a printing member carrying a plurality of printing devices 50 each having several printing faces, means for manually selectively moving the different faces of some of said devices into printing position, time clock means for moving the different faces of others of said devices into printing position, and counting 55 means for moving the printing faces of still others of said devices into printing position.

4. In a transfer strip printing and delivery machine, printing means including a reciprocable printing member carrying a plurality of printing devices each having several printing faces, means for manually selectively moving the different faces of

some of said devices into printing position, 65 rails and guides at right angles to said reciprocable printing member providing a relatively long bearing surface preventing angular displacement of said printing member during movement, and automatic means 70 for moving the different faces of others of said devices into printing position.

5. In a transfer printing and delivery machine, printing means including a printing member carrying a plurality of printing devices each having several printing faces, manually operable means interconnecting some of the printing faces for simultaneous selective movement, whereby one of the printing faces is moved into 80 printing position simultaneously with the movement of another out of printing position, time clock means for moving the different faces of others of said devices into printing position, and counting means for 85 moving the printing faces of still others of said devices into printing position.

6. In a transfer printing and delivery machine, a fixed printing table, an inking member moving adjacent the printing table, 90 means feeding a strip to be printed upon across said table between said inking member and table and delivering the same, after printing, in predetermined ticket lengths, printing means including a printing member carrying a plurality of printing devices 95 each having several printing faces, manually operable means interconnecting some of the printing faces for simultaneous selective movement, whereby one printing face 100 is moved into printing position at the time another is moved out of printing position, and automatic means for moving the different faces of others of said devices into printing position.

7. In a transfer printing and delivery machine, a fixed printing table, an inking member moving adjacent the printing table, means feeding a strip to be printed upon across said table between said inking member and table and delivering the same, after printing, in predetermined ticket lengths, printing means including a printing member carrying a plurality of printing devices 110 each having several printing faces, manually operable means interconnecting some of the printing faces for simultaneous selective movement, whereby one printing face is moved into printing position at the time another is moved out of printing position, time 115 clock means for moving the different faces of others of said devices into printing position, and counting means for moving the printing faces of still others of said devices into printing position.

8. In a transfer strip printing and delivery machine, printing means including a reciprocable printing member carrying a

plurality of printing devices each having several printing faces, manually operable means interconnecting some of the printing faces for simultaneous selective movement, whereby one printing face is moved into printing position at the time another is moved out of printing position, rails and guides at right angles to said reciprocable printing member providing a relatively long bearing surface preventing angular dis-

placement of said printing member during movement, and automatic means for moving the different faces of others of said devices into printing position.

In testimony whereof I affix my signature. 15
